HAT HOLDER

Herman Epstein, Kansas City, Mo., assignor to
Ideal Products Company

Application July 11, 1938, Serial No. 218,623

9 Claims. (Cl. 211—32)

This invention relates to hat holders and the primary object is to provide a portable hat holder which may be attached to fabric supports or to elements having smooth outer surfaces, such as automobile windows, walls of a room, or smooth woodwork, said hat holder being provided with novel securing means for engaging practically any surface, to the end that the hat holder may be conveniently placed whenever desired.

Another important object of this invention is the provision of a hat holder of the aforementioned character, which has as a part thereof, a specially formed spring which yieldably holds the clamping element of the holder in a normal position and which has a portion thereof serving as a securing element when the hat holder is to be attached to material of a nature which may be pierced by a pin.

Another important aim of this invention is to provide a hat holder which has a specially formed base plate wherein is provided an elongated opening for removably holding a suction cup, which cup may be employed to maintain the holder in operative position when the aforesaid securing element cannot be used.

A yet further aim of the instant invention is to provide a hat holder having a base plate, a clamping element, hingedly mounted thereon, and cooperating hat engaging device in the nature of laterally extended flange and a cooperating roller carried by the base plate and clamping element respectively, which flange has a plurality of nodules embossed therein to serve as gripping structures for the hat being held.

Minor objects will appear during the course of the following specification, referring to the accompanying drawing wherein:

Figure 1 is a perspective view of a hat holder embodying the present invention.

Fig. 2 is a longitudinal, central sectional view through the holder, showing the same supported by a sheet of fabric through the medium of the specially formed securing element.

Fig. 3 is an end elevation of the holder; and

Fig. 4 is an inverted end elevation of the hat holder illustrating the nature of the cooperating securing element.

The hat holder comprises a base plate 6 which is provided with a longitudinally extending slot 8 adjacent to one end thereof, and a longitudinally extending elongated opening 10 intermediate the ends of base 6. This opening 10 is appreciably narrower at one end thereof than at the opposite end, so that a conventional suction

cup 12 may have its neck 14 securely gripped when the latter is moved to the narrower end of opening 10. The wider end of opening 10 allows quick removal of the suction cup so that the hereinafter described securing element may be used in lieu of the member 12.

A laterally extending flange 16 is integral with base 6 at one end thereof. This said end is normally the lower one and the flange 16 is arranged to engage the inner face of the hat band when a hat is hung on the holder. A number of nodules 18 are embossed in flange 16 so as to serve as gripping elements for the hat.

A longitudinally arched clamping element 20 is hingedly mounted upon base 6 through the medium of pintle 22 which passes through ears 24, turned out from the longitudinal edges of base 6. One end of clamping element 20 is normally in engagement with one face of base 6 so that when a hat is in position in the holder, the brim thereof will lie between base 6 and the said end of clamping element 20. This end of clamping element 20 is provided with a unique foot structure which cooperates with flange 16 in further securing the hat in place. This foot structure comprises a bracket 26 of spring metal that is rigidly secured to clamping element 20 by tongue 28.

A roller 30 is rotatably carried by bracket 26 and normally rests against the peaks of nodules 18. When a hat is resting on flange 16, bracket 26 flexes and exerts a yielding force thereon.

Finger engaging member 32 is a part of clamping element 20 and extends upwardly and downwardly therefrom as illustrated in Figs. 1 and 2.

A barrel 34 is formed at the line of juncture between element 20 and member 32, which barrel receives pintle 22. The central portion of barrel 34 is cut away so as to provide clearance for the spring which not only serves as means for yieldably maintaining element 20 in its normal position, but provides a securing element 36.

Spring 38 has a rebent section 40 formed therein intermediate its ends, which rests against the surface of base 6. The end of spring 38, serving as a securing element 36, is sharpened and bent to present a form substantially as illustrated in Figs. 1 and 2. The U-shaped form presents one leg that may be projected through slot 8 and when in such position, may pierce a fabric sheet 42. The inherent resiliency of spring 38 has a tendency to withdraw the portion of securing element 36 which has been projected through slot 8 and therefore, a rigid assembly, including fabric 42, is afforded as a means for effectively car-

rying the hat holder. The other end 44 of spring 38 lies against one surface of finger engaging member 32 to yieldably maintain element 20 in its normal position.

- 5 The distance between securing element 36 and the back side of base 6 varies in accordance with the thickness of fabric 42 or the thickness of the supporting medium that lies between these parts 6 and 36. The resiliency of spring 38 will 10 always draw element 36 toward base 6 and the marginal edge of the glass window of an automobile or the like may be gripped between parts 6 and 36 if it is desired to hang the rack on such a support. When element 36 is hung over 15 the edge of a support, suction cup 12 serves to preclude accidental upward movement and displacement.

When element 36 is in the position shown in Fig. 2, the specially formed cooperating pin 46 20 secured to the bottom of flange 16 is forced into fabric 42. Pin 46 is soldered or welded to flange 16 as at 48, and a part of pin 46 intermediate its ends is rebent upon itself to afford a finger engaging bight 50 that projects beyond 25 the outer edge of flange 16. Pin 46 precludes lateral movement of the bottom portion of the holder after element 36 has been forced into fabric or the like 42.

In some instances it is desirable to render the 30 hat holder a permanent fixture, and when such is the case, holes 52 may be pierced through base 6 to receive nails, brads, screws, or similar fastening units.

Flange 16 is specially formed along its line of 35 juncture with base 6. A longitudinally arched groove 54 is created in flange 16 in juxtaposition to base 6 and an ear 56 is struck from flange 16 to cooperate with the arched portion of flange 16 in holding a coat hanger, the hook of which 40 is positioned behind ear 56 and in groove 54 when a hanger is to be mounted upon the holder.

An additional hook 58 is formed from material struck from base 6 and bent downwardly to a point beyond one end thereof. This hook 45 might also be utilized in carrying a coat hanger or the like, and is created without the use of additional material over that which normally is required to produce base 6.

Hat holders having appearances different 50 from that illustrated might be made without departing from the scope of the appended claims.

Having thus described the invention, what is claimed as new and desired to be secured by Letters Patent is:

- 55 1. A hat holder comprising a base plate provided with a slot therethrough adjacent to one end thereof; a clamping element; means swingably attaching the clamping element to one side of the base plate; a spring for yieldably holding 60 one end of the clamping element against said side of the base plate; and a securing element, formed by a portion of said spring, projectable through the slot in the base plate to a position beyond the other side thereof, said spring being 65 formed to yieldably urge the portion of said securing element projected through the slot toward the base plate to grip the supporting medium between the element and said base.

2. A hat holder comprising a base plate provided with a slot therethrough, adjacent to one end thereof; a clamping element; a pintle swingably attaching the clamping element to one side of the base plate; a spring yieldably holding one 70 end of the clamping element against said side of the base plate; and a securing element formed

on one end of the spring projectable through the slot in the base plate, to a position beyond the other side thereof, the other end of said spring being in engagement with said clamping element near the other end of the same, a portion of said spring intermediate its ends being wound around the said pintle, said spring having a rebent section in its intermediate portion, bearing against the said base plate for the purpose specified. 10

3. A hat holder comprising a base plate; a laterally extending flange on the plate at one end thereof; a clamping element swingably mounted on the plate; means for yieldably holding one end of the clamping element against one 15 side of the base plate close to the flange; and a transversely arched marginal area forming a groove in the flange along the line of connection with the base plate the remaining part 20 of said flange being flat.

4. A hat holder comprising a base plate; a laterally extending flange on the plate at one end thereof; a clamping element swingably mounted on the plate; means for yieldably holding one end of the clamping element against one 25 side of the base plate close to the flange; a longitudinally arched marginal area forming a groove in the flange along the line of connection with the base plate; and an ear struck upwardly from said flange adjacent to the groove intermediate the ends thereof, said ear being on the opposite side of said groove from the base plate for the purpose specified. 30

5. A hat holder comprising a base plate provided with a slot and a longitudinally disposed 35 opening therethrough intermediate the ends thereof; a laterally extending flange on the plate at one end; a clamping element swingably mounted on the plate; a spring for yieldably holding one end of the clamping element against 40 one side of the base plate close to the flange; a U-shaped securing element formed on one end of the spring and disposed so that one leg thereof is projected through the slot in the base plate, and a suction cup removably fitted into the opening at one end thereof. 45

6. A hat rack comprising a flat base plate; a laterally extending flange on the plate; an arched clamping element pivotally secured to the base plate adjacent the end thereof remote from said 50 flange; a resilient foot structure on the clamping element cooperating with said flange, when in the normal position, to grip the crown of a hat; a spring yieldably maintaining said element in the normal position; and a finger-engaging member on the clamping element. 55

7. A hat rack comprising a flat base plate; a laterally extending flange on the plate; an arched clamping element pivotally secured to the base plate adjacent the ends thereof remote 60 from said flange; a resilient foot structure on the clamping element cooperating with said flange, when in the normal position, to grip the crown of a hat; a spring yieldably maintaining said element in the normal position; and a finger-engaging member on the clamping element, the arched clamping element being to one side of the base plate, said finger-engaging member extending upwardly and outwardly from the pivotal connection. 65

8. A hat rack comprising a base plate; a laterally extending flange on the plate; a clamping element swingably mounted on the plate; a resilient foot structure on the clamping element adjacent to the flange when the clamping ele- 70 75

ment is in the normal position; and a spring yieldably maintaining said element in the normal position, said foot structure comprising a bracket of resilient material and a roller held in projected relation with the clamping element by said bracket.

9. A hat rack comprising a flat plate; a laterally extending transverse flange on the plate; an arched clamping element pivotally secured to the base plate adjacent the end thereof remote from said flange; a resilient foot structure on the clamping element cooperating with said flange,

when in the normal position, to grip the crown of a hat; a spring yieldably maintaining said element in the normal position; and a finger-engaging member on one end of the clamping element, the said foot structure being carried by the said clamping element and comprising a resilient bracket anchored to the other end of the clamping element and extending downwardly and outwardly toward said laterally extending flange, and a roller mounted on the bracket.
